UNITED STATES PATENT OFFICE.

GEORGE FAIR, OF BOSTON, MASSACHUSETTS, ASSIGNOR TO THE FAIR LOOM ATTACHMENT COMPANY, OF SAME PLACE AND PORTLAND, MAINE.

MISPICK AND SMASH PREVENTER FOR SHUTTLES.

SPECIFICATION forming part of Letters Patent No. 611,213, dated September 20, 1898.

Application filed August 27, 1897. Serial No. 649,717. (No model.)

To all whom it may concern:

Be it known that I, GEORGE FAIR, of Boston, in the county of Suffolk and State of Massachusetts, have invented certain new and 5 useful Improvements in Mispick and Smash Preventers for Shuttles, of which the following is a description sufficiently full, clear, and exact to enable those skilled in the art to which it appertains or with which it is most 10 nearly connected to make and use the same.

This invention has relation to means embodied in the construction of a shuttle to adapt it to effect the stopping of a loom just before the weft or filling is exhausted from 15 the cop or bobbin in the shuttle in order at that time to prevent a broken or mis pick and the consequences thereof in the fabric produced.

The terms "broken pick," "partial pick," 20 and "mispick" are employed herein in their technical or "shop" sense, the former terms indicating a partial pick of the weft-thread and the last term meaning no pick or the entire absence of a weft or shuttle thread in the 25 shed after the passage of the shuttle.

The means commonly employed prior to my invention to stop the loom when the weft failed, either from being broken or from running out from the cop or bobbin in the shuttle, was the weft-fork. With this device so long as the weft remained intact the weft-fork was tilted on its pivot and escaped, being acted upon by the knocking-off means; but when the weft broke or ran out, as before indicated, there being no weft present to actuate or tilt the fork, the loom was knocked off or stopped.

As the weft-fork in existing machines is arranged to be operated upon between the 40 selavage of the cloth being woven and the shuttle when in the shuttle-box, it will be understood that in the operation of the loom the latter will not be knocked off until after the weft-thread fails and the shuttle has completely traversed the shed and has landed in its box, thus nearly always resulting in a 45 broken pick or a mispick.

In the weaving of all fabrics if a broken or mis pick is allowed to go uncorrected the cloth 50 produced will be imperfect and be subject to discount in sales. In case the matter is cor-

rected at the time of weaving the cloth the broken pick must of necessity be picked out and the loom turned back to find the proper shed in order to enable the weaver to go on 55 again in an orderly way in the production of perfect goods. All this occasions considerable wastage and much loss of time, as is well known to weavers and those skilled in the operation of looms.

Prior to my invention the mischief of a broken pick or a mispick, as I have already stated, nearly always occurred when the weft or filling thread was exhausted from the cop or bobbin in the shuttle. By my improvements the loom is controlled by mechanical means from means in the shuttle, so as to obviate or prevent the aforesaid mischief at the time mentioned. At other times than when the weft or filling is nearly exhausted from 70 the shuttle—as when, for instance, the weft-thread breaks with a substantial supply still in the shuttle—the commonly-employed weft-fork or other known means will be relied upon to detect broken picks and mispicks.

In addition to preventing partial and mispicks when the filling-thread from the shuttle is nearly exhausted my invention serves the purpose of preventing "smashes" by the lodgment of the shuttle in the shed or from 80 the failure of the shuttle being sent fully "home" in its box.

To these ends my invention consists of the improved shuttle and its equipment and to means coacting therewith whereby the specified results or functions are attained, as will 85 hereinafter fully appear.

Reference is to be had to the annexed drawings, and to the letters marked thereon, forming a part of this specification, the same letters designating the same parts or features, as the case may be, wherever they occur.

Of the drawings, Figure 1 is a plan view of a simple form of my invention, showing the same as though applied to a certain form of 95 shuttle and as though the shuttle were in the box and the invention operating on a finger or rod extending up from a rock-rod, which may be or act like a protection-rod to knock off a loom to effect a stopping of the same. 100 Fig. 2 is a front view of Fig. 1, a part of the shuttle being broken out to show the man-

ner in which the inner end or portion of the feeler finger or rod forming a part of my invention may be constructed to rest or be brought to bear upon the base of the cop. 5 Fig. 3 is a plan view somewhat similar to that of a portion of Fig. 1, but showing the yarn on the spindle or quill in the shuttle as though nearly exhausted or run out. Fig. 4 is a diagrammatic front elevation, partially in section, of the lay of a loom and some of its immediate connections, showing the manner in which the several parts may be related with respect to my invention, the shuttle-binder or swell being represented as cut off. Fig. 5 10 is a diagram, on a small scale, of my invention as applied to a shuttle operating in a box provided with a swell or binder. Fig. 6 is a plan view of part of a shuttle provided with my invention, showing the manner in which 15 the latter co-operates with a bobbin instead of a cop in the shuttle, the bobbin in this figure being shown as full. Fig. 7 is a view similar to Fig. 6, but showing the yarn as nearly exhausted from the bobbin, parts being shown 20 as in section or as broken out. Fig. 8 is a front elevation of what is represented in Fig. 7. Fig. 9 is a detached view of the swell on a shuttle-box, showing how the same may be slightly modified in form in the use of my invention, as shown in Fig. 5. Fig. 10 is a side elevation of a portion of the end of a shuttle provided with my improvements, parts being shown as broken away and the shuttle being 25 shown as provided with a split spindle to hold the cop thereon, the split in the spindle extending through the latter horizontally, and showing how the said opening or split in the spindle may be utilized in connection with my invention. Fig. 11 is a plan view of what 30 is shown in Fig. 10. Fig. 12 is a view similar to what is represented in Fig. 11, but showing the yarn on the spindle as having been exhausted to an extent that will permit my invention to effect the stopping of the loom 35 before the yarn is entirely run out or exhausted. Fig. 13 is a sectional view taken on the line 15 15 of Fig. 12.

Referring first to Figs. 1 to 4, inclusive, *a* designates the loom-frame. *b* is the lay. *c* is 40 the shuttle-box. *d* is the picker-stick. *e* is the protection-rod arranged below the lay, or for that matter it may be any suitably-arranged rock-rod (spring-actuated in one direction, as is the usual protection-rod on a loom) 45 adapted to act as a knock-off for the loom, and *f* is the shuttle. All the parts so far mentioned are of usual construction and function or of such construction as to come within the skill of an ordinary mechanic, excepting the shuttle when equipped with my 50 improvements, to be presently explained.

The leading feature of my invention is a feeler-finger *g*, with which I equip the shuttle so that one part (as the inner or free end portion) *h* shall rest upon the yarn of the cop or bobbin in the shuttle in such manner 55 that such part *h* shall ultimately be brought

to bear upon nearly the last of the coils of the yarn to be drawn off, another portion of the body of the feeler-finger projecting beyond the 70 substantially extreme outlines of the body of the shuttle so long as the inner or free end portion rests upon the said coils of yarn. As is shown in the drawings, the feeler-finger *g* may be made of sufficiently stout wire, be hinged 75 to the shuttle at one end, as at *i*, swell outward, as at *j*, through a slot *g*' in the shuttle or otherwise beyond the extreme outlines of the shuttle, and at its other end or end portion rest upon the base of the cop or bobbin *k*. As is 80 clearly indicated at *l* in Fig. 2, I prefer, though it is not essential, to form an angular offset in the inner end portion *h* of the feeler-finger *g*, in order to give the said feeler-finger greater throw in its operation and more bearing-surface on the yarn. 85

m designates a finger connected at its lower end with a rock-rod *e* and extending up inside of the shuttle-binder or swell or within the shuttle-box in the path of travel of the 90 swell portion *j* of the feeler-finger *g* on the shuttle. When the inner end of the feeler *g* rests upon yarn on the cop, the swell *j* will be held out beyond the outline of the shuttle at the point where the said swell is located and 95 act upon the finger *m* to move it back, rock the rod *e* to the extent that the finger *m* is moved back, and so prevent the dagger *e*' on the rod *e* from operating the stop-motion mechanism to stop the loom and hold the lay 100 back, and this operation will continue even when the yarn of the cop runs as low on the spindle of the shuttle as is shown in Fig. 3. When, however, the shuttle (with the yarn as low as represented in Fig. 3) is picked 105 through the shed again and back, the yarn will be drawn off the shuttle spindle or quill from under the inner end of the feeler-finger *g*, and the latter will be allowed to be pressed inward, so as to be inefficient by way of a 110 means for acting on the finger *m* to rock the rod *e* and thus effect the stoppage of the loom and the holding back of the lay, and this operation will take place, as before said, even though there may yet be, as in practice there 115 will be, yarn enough in the shuttle to prevent the weft-fork from knocking off the loom before, say, two full picks are made.

It will be seen that my invention may be employed for the specific purpose mentioned—that is, for stopping the loom just before the yarn from the shuttle is exhausted—and thus avoiding mis or broken picks at that time, as well as that for effecting the knocking off of the loom to prevent smashes. 120 125

In using the invention to prevent smashes it will be understood that the finger *m* will be connected with the protector-rod the same as the usual finger employed as it has heretofore been to be acted upon by the shuttle-binder or swell, excepting that it is made to extend up on the inner side of the swell, as shown in Figs. 5 and 6, so that if the shuttle should become lodged in the shed or should 130 135

fail to fully enter the shuttle-box the finger *m* will not be pressed back by the swell *j* of the feeler *g*, and hence the loom will be knocked off. Detailed illustration and description of the stopping and all of the knocking-off mechanism is not herein given, since it forms no part of my invention and since such mechanism, in connection with the protector-rod, is well understood by weaving-
o artisans.

In Fig. 5 the shuttle is shown as in its box and the swell *n* as operating thereon in the usual way, excepting that it does not assist in controlling the protection-rod. The swell *n*, however, is slightly modified in form to permit of the use of my invention, the said modification consisting in forming a shallow longitudinal groove *o* on the inner face of the swell and making a vertical groove *p* also in
15 the said inner face, (see Fig. 9,) back into which groove *p* the finger *m* may move by the action thereon of the swell *j* of the feeler-finger *g*, the groove *o* affording means for the swell *j* of the feeler-finger *g* to pass without
20 serious contact with the shuttle-box swell *n*.

It will be noted that the finger *m* can be set on the protector-rod so that the latter may be allowed to operate sooner or later with respect to the amount of yarn on the spindle
30 or bobbin, and it is desirable to form the shuttle *f* as is shown in Figs. 6 and 7, wherein the shuttle-body is portrayed as having a recess *q* opposite the point where the swell *j* occurs in the feeler-finger *g* and opposite the
35 point where the latter feeler-finger acts on the said finger *m*, so that the swell *j* may be brought entirely within the line of the extreme front face of the shuttle, though still swell outward beyond the outlines of said recessed portion *q*.

In Figs. 6, 7, and 8 I have shown my invention as applied to a shuttle adapted to carry a bobbin *r* instead of a cop, as shown in Figs. 1, 2, and 3. In this case the construction and mode of operation will be substantially the same as that hereinbefore described in connection with the cop; but it will be seen, particularly by reference to Fig. 7, that the amount of yarn to be left upon
45 the spindle of the bobbin may be graded or regulated with the utmost nicety. Supposing that the inner end of the feeler-finger *g*, resting upon the yarn, were not to be allowed to move far enough inward to allow the rod
50 *e* to be operated to knock off the loom until all the yarn was drawn from under said end, it will be seen that the shuttle might reach the box with but one or two rounds of yarn on the bobbin and not sufficient for it to be
55 picked across the shed and back again without running out. In this case a groove *s* may be formed in the base of the bobbin, and yarn sufficient to form at least two picks may be wound therein, so that the shuttle will with
60 the utmost certainty stop on a particular side of a loom—say the left-hand side—after all but one or two rounds or coils of yarn under

the inner end of the feeler have been drawn off from the bobbin. In Fig. 6 the bobbin is shown as full, and in Fig. 7 a representation
70 is made of the yarn being drawn off the bobbin down next to the feeler-finger, as I have described. In said Fig. 8 through the part broken away there is shown a bobbin in the shuttle with sufficient yarn thereon to pick
75 across the shed and back without employing the yarn in the groove *s*.

In Figs. 10 to 13, inclusive, I have shown my invention as applied to a shuttle provided with a split spindle upon which to hold the
80 cop. In this case the spindle will be so arranged as that the split or opening *v* in the spindle may extend horizontally or face outward—that is, toward the operator standing in front of the loom—and the feeler-finger *g*
85 will have its inner end so constructed as that when the yarn is drawn off the spindle from under the inner end of the finger said inner end will move into or through the slot *v* of the spindle, as shown in Fig. 12. In this
90 case the inner end of the feeler-finger is curled, as at *w*, such curled end being filed or cut down, so that it may move within the slot quite readily or easily.

These illustrations serve to show that with
95 a little care in the manner of winding the yarn on the base of the bobbin or cop the invention may be employed so as to knock off the loom at any particular time with reference to the amount of yarn remaining on the
100 spindle or bobbin.

In building a cop for special use in connection with my invention in split spindles, such as are shown in Figs. 10 to 13, inclusive, the winding may commence at a point above the
105 base—say at the point *x*—and then wound down to the base, where the building of the cop may commence. In this instance coils of
110 yarn would extend from the point *x* to the base, and the loom would be sure to be knocked off at a particular point—that is, with a particular number of coils still wound on the spindle.

My improvement in a shuttle enables it, just before the yarn is completely exhausted,
115 to give the initial movement to mechanism in order to stop the loom, or it may as well be to set in motion some auxiliary mechanism to secure other results in connection with the operation of weaving. I therefore do not confine myself to any use that may be made of the invention, whether specified herein or not.

With my invention so long as the next to the last of the yarn to be drawn from the shuttle remains therein, and which yarn acts upon the feeler-finger *g*, a swell portion of the latter will be held outward to an appreciable extent beyond the bounds or outline of the shuttle where the swell occurs, and when the aforesaid portion of the yarn is drawn off, so
125 that it may no longer influence the position of the feeler-finger, the swell or portion formerly extending beyond the bounds of the shuttle may be moved inward within the same.

It is to be understood in connection with the foregoing that no part of the swell or outwardly-extending portion of the feeler-finger will have a projecting end or other feature 5 that would be liable to catch upon the threads of the warp or otherwise render it inoperative as the shuttle is picked through the shed.

By extending the feeler-finger *m* up inside of the shuttle-binder or swell *n* I am enabled 10 to secure the action of the swell of the feeler-finger *g* directly upon the said feeler *m* and not through the medium of the shuttle-binder or other means. This is an important feature 15 of the invention, since it enables me to accomplish results that could not otherwise be readily attained—such, for example, as employing the invention to prevent smashes, as hereinbefore described.

It will be observed that with my invention 20 smashes are prevented when the shuttle is partially boxed, so as to press the binder *n* outward, but still with the inner end of the shuttle extending into the shed, as well as when the shuttle is entirely lodged in the shed. This 25 important function is not accomplished, in the emergency mentioned, by the commonly-employed means for preventing smashes.

It is understood that the protector-rod is the initial part of the stopping or knocking 30 off, and in some cases with other auxiliary means, and that the finger *m* is operatively connected with the protector-rod.

It will be borne in mind that it is not intended herein to convey the idea that broken 35 picks or mispicks are prevented by my invention at any other time than when it becomes necessary to resupply the shuttle with weft or filling yarn.

Having thus explained the nature of the invention and described a way of constructing 40 and using the same, though without attempting to set forth all of the forms in which it may be made or all of the modes of its use, it is declared that what is claimed is—

45 1. A shuttle provided with a recess, *q*, in its face and a slot formed through the front wall of the body of the shuttle at the said recessed point, combined with a feeler-finger provided with a swell adapted to extend 50 through the slot, the said feeler-finger being pivoted at one end to the body of the shuttle

and adapted at a point in its free portion to rest upon the next to the last of the yarn to be drawn from the shuttle.

2. A shuttle provided with a slot formed 55 through its front wall, combined with a feeler-finger provided with a swell adapted to extend through the slot, the said feeler-finger being pivoted at one end to the body of the shuttle and adapted at a point in its free portion to rest upon the next to the last of the 60 yarn drawn from the shuttle, the shuttle-binder or swell, and a finger, *m*, arranged to extend up inside of the binder in the path of travel of the swell of the said feeler-finger to 65 be directly acted upon by it, and means under the control of the finger *m* for stopping the loom.

3. A shuttle provided with a slot formed 70 through its front wall, combined with a feeler-finger provided with a swell adapted to extend through the slot, the said feeler-finger being pivoted at one end to the body of the shuttle and adapted at a point in its free portion to rest upon the next to the last of the 75 yarn drawn from the shuttle, the shuttle-binder or swell provided with longitudinal and vertical grooves, as described, and a finger *m* arranged to extend up inside of the binder in the path of travel of the swell of the 80 said feeler-finger to be directly acted upon by it, and means under the control of the finger *m* for stopping the loom.

4. A shuttle equipped with a split spindle, the split in the spindle extending horizontally 85 therethrough and the shuttle being provided with a recess *q* in its face and a slot formed through its front wall at the said recessed point, combined with a feeler-finger provided with a swell adapted to extend through the 90 slot, the said feeler-finger being pivoted at one end to the body of the shuttle, and adapted at its free end to move into the split of the spindle when the yarn is drawn off therefrom.

In testimony whereof I have signed my 95 name to this specification, in the presence of two subscribing witnesses, this 23d day of August, A. D. 1897.

GEORGE FAIR.

Witnesses:

ARTHUR W. CROSSLEY,
ANNIE J. DAILEY.
